UNITED STATES PATENT OFFICE.

JOHN CARNEY, OF PAWTUCKET, RHODE ISLAND.

DEVICE FOR WITHDRAWING CLOSURE-CAPS FROM MILK-BOTTLES.

1,141,378.

Specification of Letters Patent. Patented June 1, 1915.

Application filed May 6, 1914. Serial No. 836,615.

To all whom it may concern:

Be it known that I, JOHN CARNEY, a citizen of the United States, residing at Pawtucket, in the county of Providence and State of Rhode Island, have invented certain new and useful Improvements in Devices for Withdrawing Closure-Caps from Milk-Bottles, of which the following is a specification.

10 My invention relates to devices for withdrawing the paste-board caps or seals from closed milk bottles, and it consists in the novel construction and arrangement of the parts, substantially as hereinafter set forth and claimed.

15 In uncapping devices of the general character referred to the means usually employed consist of an independently removable base or frame carrying a pin or member having its lower or free end arranged to puncture the cap. In such former devices the user holds the same in place or position with one hand while manipulating the puncturing element with the other to remove the 20 cap from the mouth of the bottle or jar. As thus constructed the device, together with the cap itself, are liable to drop from the container and become more or less soiled and infected with foreign matter. Such 25 former devices, too, are comparatively expensive to manufacture.

30 In my improved bottle uncapping device the construction is extremely simple and inexpensive; it is adapted to be permanently connected to the bottle, the latter being of well-known construction; the wire bail or frame of the device is adapted to swing through a circular arc and carries with it a permanent spear-shaped member adapted, 35 when punctured through the cap, to bear on the bottle when the frame is swung downwardly, thereby acting as a lever for forcing the cap from the bottle, the cap being retained on the spear element. After 40 pouring from the bottle the desired quantity of its contents the device can be readily swung back to its normal position, the user at the same time guiding the cap to close the bottle's outlet, the operation being repeated 45 as often as desired or while any of the contents remain in the bottle. The frame also serves as a convenient bail or handle for carrying the container.

45 In the accompanying drawing, Figure 1 50 represents a vertical, longitudinal sectional view, taken through the center of the upper

portion of a bottle or jar, showing the uncapping device in various positions; Fig. 2 is a front view of the device, detached from the bottle; and Fig. 3 represents a modification.

55 B indicates the neck portion of a milk-bottle or jar of usual construction having its upper end *b* enlarged peripherally and provided with a recessed inner seat *b*² through 60 which the mouth or outlet *b*¹ extends. A removable closure cap *c* of suitable material, as paste-board, is mounted air tight on said seat, all substantially as usual in containers of this character. The same cap or closure 65 members are not, of course, well adapted for reuse after the containers have been refilled.

70 The device A, forming the subject of my invention, has a frame or bail member formed from a length of comparatively stiff 75 wire bent to an inverted U-shape; the same having oppositely disposed parallel arms *a* *a* united at the top by a tie or bridge *e* on which the cap-impaling spear member *d* is loosely supported. The lower ends *a*¹ of 80 said arms are adapted to be pivotally mounted and supported in a wire band *f* encircling the neck of the bottle. The member *d* is prevented from sliding movement on the tie *e* by means of a bend *e*¹, shown in Fig. 2, 85 or by tubular collars *e*², Fig. 3.

90 The puncturing member *d* is permanently connected to the said yoke or bail and swings with it from the pivots *a*¹, and is also capable of independent axial movement on the tie or bar *e* of the frame. The lower end portion of member *d* has a reduced longitudinal shank part *d*¹ limited by the upper and lower shoulders *d*² *d*³ and having the extreme lower end terminating in the spur 95 or spear *s*.

95 The manner of operation is substantially as follows: The fluid-filled container B having the cap unseating device attached thereto is normally ready for instant service. 100 When not in use the bail may rest against the wall of the bottle, as indicated by dotted lines at *o*; now, in order to withdraw the cap *c* from the bottle, the user swings the spear-carrying bail on the pivots or trunnions *a*¹, at the same time swinging the spear *d* on its pivot until its end *s* engages the desired part of the surface of the cap, followed by a further swinging movement 105 of the bail, which action forces the spear through the cap and impales it on the shank *d*¹, substantially as indicated at position 1; 110

the continued arc movement of the members, say to the dotted line position 2, causes the spear *d* to bear firmly against the upper end of the bottle (the space between the arms *a* exceeding the diameter of the beaded end *b*). A slight prying pressure downward upon the bail quickly unseats the cap, the spear, with the cap thereon, swings on the axis *e*¹ about 180°, so that at the end of the 10 arc movement the bail will bear against the bottle substantially as indicated by dotted lines, see position 3; the underside *x* of the cap then being outward. A reversal of the operation returns the parts to the position 1 15 if the cap is to be temporarily reused, and to the normal position *o* in case the bottle is to be refilled and resealed.

I claim as my invention and desire to secure by United States Letters Patent:—

20. 1. A device for uncapping milk-bottles or other analogous containers, the same consisting of a metal bail or frame having a transverse tie or bar terminating in oppositely disposed arms extending at substantially right angles therefrom, a spear-like piercing element permanently supported and axially movable on said tie, the free end portion of said spear adapted, when in use, to be pressed through the cap to withdraw 25 the latter from the container and retain said cap impaled thereon, and means for securing the frame to the container, said securing means having the frame pivoted thereto and capable of swinging arcuate movements 30 thereon.

25. 2. In a device for withdrawing the caps or seals from the mouth of milk-bottles or like containers, the combination of a bail

or frame having downwardly extending arms arranged to be pivotally connected to the outer neck portion of the container, said bail having a tie integral therewith uniting the upper portion of said arms and capable of swinging across the mouth of the bottle, and a cap-piercing element carried by said tie arranged for independent turning movement on the latter, for the purpose herein set forth.

3. The combination of a bent bail or frame, a band having the frame pivoted thereto adapted to be permanently connected to the neck of a container, a member arranged to pierce and remove the cap or closure from the container, said piercing member being mounted to turn axially on 50 said bail, and means for maintaining the piercing member in position on the bail against lateral movement.

4. In a device of the character described, the combination with a bottle having its 55 neck provided with a discharge opening extending through a recessed annular seat, of a bail arranged for swinging movement indirectly pivoted to the exterior of said neck, a piercing member permanently pivoted to 60 and movable bodily with the bail, said piercing member also capable of independent movement on the bail, and means for centralizing or positioning the piercing element 65 on the bail.

In testimony whereof I have affixed my signature in presence of two witnesses.

JOHN CARNEY.
